John H. Hartman.

UNITED STATES PATENT OFFICE.

JOHN H. HARTMAN, OF LANCASTER, PENNSYLVANIA.

SUPPORT AND CLAMP.

1,124,896.

Specification of Letters Patent.

Patented Jan. 12, 1915.

Application filed October 2, 1914. Serial No. 864,639.

To all whom it may concern:

Be it known that I, JOHN H. HARTMAN, a citizen of the United States, residing at Lancaster, in the county of Lancaster and 5 State of Pennsylvania, have invented certain new and useful Improvements in Supports and Clamps, of which the following is a specification.

This invention relates to supporting legs 10 for articles and means for securing said legs tightly in position and is especially applicable to toys.

The objects of this invention are to provide a simple leg member and means for 15 fitting the same in place and holding it in such position with the least number of parts, thus obtaining the advantages of simplicity, strength, durability, low cost of manufacture and quick assemblage, which objects are 20 accomplished by the construction, arrangement and combination of parts hereinafter more particularly set forth and claimed.

The invention will be herein illustrated and described as applied to a toy bank of 25 spherical form; but it may equally well be applied to other articles, including toys, of various shapes with but slight and obvious modifications to adapt it to the particular article in view, and I therefore do not wish 30 to be understood as limiting myself to any particular article or form of article, the present drawing and description being merely by way of illustration of its application to some useful object.

35 In the accompanying drawings: Figure 1 represents a perspective view of a toy bank embodying my invention; Fig. 2, a central vertical cross section; Fig. 3, a similar view at right angles to Fig 2; Fig. 4, an interior view of the lower member, or plate, showing the side slots and recesses to receive the lugs 40 of the legs; Fig. 5, a similar view of the upper member or plate showing the corresponding recesses in its edge to receive the upper part of the upper lugs of the legs; and 45 Fig. 6, a detail of the upper part of one of the legs.

In the present embodiment the legs are arranged on a slanting line and their lugs are 50 formed in accord therewith.

Referring now in detail to the drawings, 1 indicates the upper plate of the bank body, 2 the lower plate, both plates being semi-spherical in shape and fitting together at 55 their edges, 3 a bolt and nut to hold said plates firmly together, and 4, the legs.

These legs 4 are each provided with a downwardly presented lug 5 and an upper lug 6, which is square in cross-section and is presented inwardly and provided at its inner end with an integral downward projection 7.

The lower plate 2 is provided with three slots 8 and three right angle recesses 9 in its edges, each slot 8 and its corresponding recess 9 being in a line, and is further provided with two semi-circular recesses 10 to receive the correspondingly shaped co-operative positioning lugs 11 formed on the edge of upper plate 1. The upper plate 1 is similarly provided with three right angle recesses 12 in its edge, equally spaced and of the same size as recesses 9 so as to register with the latter and form square apertures therewith. The upper plate 1 is further provided with a slot to receive coins and a hole 13 to permit the passage of bolt 3 and the lower plate 2 is similarly provided with a hole 14 to permit the passage of the bolt 3, said hole 14 passing through the center of a square recess 15 which is adapted to receive the nut and keep it from turning, thus facilitating the assemblage of the parts and preventing the turning of the nut after the parts have been assembled.

The parts are assembled as follows: First the legs 4 have their lugs 5 and 6 fitted into the slots 8 and the recesses 9 respectively, so that the lower part of the lugs 5 and the projections 7 engage the adjacent part of the 90 interior face of plate 2, the upper plate 1 is then positioned so that its lugs 11 fit into the recesses 10 and its recesses 12 receive the upper half of the lugs 6; and finally, the bolt 3 is passed through holes 13 and 14 and 95 turned so that its screw-threads engage the screw-threads of the nut held in recess 15 and draw the two plates 1 and 2 tightly together, thus firmly clamping them in the upper lugs 6 and holding all parts firmly in 100 place. It is apparent that, with this construction, none of the lugs can be displaced until the plates 1 and 2 are separated and therefore that the legs will be likewise immovable as they are integral with the lugs.

Having thus described my invention, what I claim as new and desire to secure by Letters Patent is:

1. An upper plate and a lower plate, said plates fitting together and the lower plate 110 being provided with slots in its sides, in combination with legs having lugs passing

through said slots and engaging the lower plate adjacent said slots, and provided with other lugs passing between said plates, and means for drawing said plates together to 5 clamp on the latter lugs.

2. An upper plate and a lower plate, said plates fitting together and the lower plate being provided with slots in its sides and recesses, in combination with legs having 10 two sets of lugs, one set passing through their respective slots to engage said lower plate and the other set fitting into said recesses to engage said lower plate, and means for clamping the plates together on the last 15 mentioned set of lugs.

3. An upper plate and a lower plate both provided with correspondingly shaped registering recesses and the lower plate being provided with slots, in combination with 20 legs, each leg being provided with two lugs entering their respective slot and recesses of said plates and engaging the adjacent part of the inner face of the lower plate, and means for drawing said plates tightly together. 25

4. An upper plate and a lower plate both provided with correspondingly shaped reg-

istering recesses and the lower plate being provided with slots, in combination with legs each of which is provided with a lower 30 lug and an upper lug, the lower lug passing through its respective slot and engaging the inner face of the lower plate and the upper lug entering its respective registering recesses in said plates and having a downward 35 projection engaging said lower plate, and means for holding said plates in position to clamp each of the upper lugs between them.

5. A lower plate and an upper plate adapted to fit together at their edges, both 40 being provided with registering recesses in said edges and the lower plate being provided with slots in line with said recesses, in combination with legs provided with lugs 45 passing through their respective slots and recesses and means for clamping said plates together on one lug of each leg.

In testimony whereof, I have signed my name to this specification in the presence of two subscribing witnesses.

JOHN H. HARTMAN.
